UNITED STATES PATENT OFFICE.

GEORGE H. BUCHHEIMER, OF BALTIMORE, MARYLAND.

DESIGN FOR A HANDLE FOR SATCHELS OR BAGS.

No. 37,682.

Specification for Design.

Patented Nov. 21, 1905.

Application filed September 27, 1905. Serial No. 280,368. Term of patent 7 years.

To all whom it may concern

Be it known that I, GEORGE H. BUCHHEIMER, a citizen of the United States, residing at Baltimore, in the State of Maryland, have invented a new, original, and ornamental Design for a Handle for Satchels or Bags, of which the following is a specification, reference being had to the accompanying drawing, forming part thereof.

The figure is a side elevation showing my new design.

I claim—

The ornamental design for a handle for satchels or bags, as shown.

GEORGE H. BUCHHEIMER.
